J. D. PEDERSEN,
FIREARM,
APPLICATION FILED DEC. 13, 1919.

1,410,267.

Patented Mar. 21, 1922.

Inventor:

John D. Pedersen,
By his Atty, J. H. Richards. —

UNITED STATES PATENT OFFICE.

JOHN D. PEDERSEN, OF JACKSON, WYOMING.

FIREARM.

1,410,267.

Specification of Letters Patent. Patented Mar. 21, 1922.

Application filed December 13, 1919. Serial No. 344,679.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms which is usually designated as small arms, and a principal object of the invention is to furnish an improved grip-safety device particularly applicable to auto-loading and automatic pistols.

15 One class of small arms to which my present improvements are applicable, includes the auto-loading pistols having a grip-stock or handle-portion of the frame or receiver of the firearm, which is adapted 20 to receive a safety device operable by hand grip or compression.

An improved auto-loading pistol of this kind is described in my Patent No. 1,348,733, dated August 3, 1920, and granted on my 25 copending application (renewal) Serial No. 311,689, filed July 17, 1919. Therefore, for convenience of illustration, I have herein shown my present improvements as arranged and applied to the particular kind 30 of auto-loading pistol which is shown in the drawings of "said patent, to which reference may be had.

The features of my grip-safety device are that it is a grip, or handle contained, safety 35 device arranged to prevent discharge of the firearm by locking the firing member or hammer and the trigger-sear, when my grip-safety device is in normal position or position of safety.

40 Also, where the firearm is provided with a sliding breechaction comprising a firing-pin to prevent discharge of the fire-arm by locking the breechaction to prevent contact between the firing-pin and the cartridge, so 45 that action of the firing member or hammer on the firing-pin will not explode the cartridge, this being accomplished by a member which blocks a slidable member or controller in position to lock such sliding 50 breechaction when my grip-safety device is in normal position or position of safety, said blocking member being actuated by a grip-operable member; the slidable member being releasable from position locking the 55 breechaction by grip-compression of the grip-operable member which moves a mem-

ber or block-lever, intermediate between the grip-operable member and said blocking member, into contact with said blocking member and into contact with a trigger 60 member, so that subsequent movement of the intermediate member or block-lever by pressure on the trigger-member will release the blocking member from engagement with said slidable member or controller. 65

Another feature of my invention is that when the slidable member or controller is, through engagement with a blocking member, in position locking the sliding breech- 70 action of the firearm, and my grip-safety device is in normal position or position of safety, the slidable member or controller is releasable from such locking position by grip-compression of a grip-operable mem- 75 ber which moves a member or block-lever, intermediate between the grip-operable member and the member for locking the slidable member or controller, into contact with such blocking member and into con- 80 tact with a trigger member which is also engageable with a sear member so that subsequent pressure on the trigger-member will release the blocking member from engagement with said slidable member or controller, and will move the sear member to re- 85 lease the firing member or hammer to discharge the firearm.

In the accompanying drawings, which illustrate an embodiment of my grip-safety 90 device, Figure 1, is a side elevation, partly broken away, of a pistol provided with my grip-safety device, the grip-operable member or grip-safety member thereof being in normal position or position of safety, the 95 sliding breechaction of the pistol being locked, and the firing member or hammer being in firing position.

Figure 2, is a fragmentary side view, on a larger scale than Fig. 1, of the rear portion of a pistol provided with my grip-safety device, showing the details, the grip-operable member or grip-safety member thereof being compressed, my device being in position preparatory to release of the 105 member for locking the sliding breechaction of the pistol and the sear member by trigger pressure, the firing member or hammer being in firing position.

Figure 3, is a fragmentary side view on 110 substantially the same scale as Fig. 2, showing the details of the rear end of a pistol

provided with my grip-safety device, the grip-operable member or grip-safety member thereof being compressed, my device being in position wherein the member for locking the sliding breechaction of the pistol and the sear member have been released by trigger pressure, the firing-member or hammer being in fired position.

Figure 4, is a rear end sectional view, on the line 4—4 of Fig. 3, looking in the direction of the arrow, showing the details, of a pistol provided with my grip-safety device, the grip-operable member or grip-safety member of my device being removed.

Figure 5, is a front end sectional view, on the line 5—5 of Fig. 2, looking in the direction of the arrow, showing the details of the rear end of a pistol provided with my grip-safety device, a front end portion of the grip-stock of the pistol being removed, and the slidable member or controller being in position for locking the sliding breech action of the pistol.

Similar reference characters or numerals refer to similar parts throughout the several views.

My grip-safety device, generally denoted by G, comprises a grip-operable member or grip-safety member G' provided with a frame-rib 10. The grip-safety member G' and frame-rib 10 are attached at the lower end thereof by a pivot-pin g to the grip-stock of the pistol, the grip-stock of the pistol being bored or otherwise cut away at 2°, to receive the grip-safety member G'. The upper end G² of the grip-safety member G' is engageable with the frame of the pistol, the grip-safety member G' being hand compressible or yieldable. The grip-safety member G' closes the slot or space 2°, which slot or space is of use in assembling the details of my invention.

The firing member or hammer H is pivotally secured to the frame of the pistol and is movable to firing position and to fired position. The firing member or hammer H is provided with a firing-notch or cock-notch 8° and with an eccentric cam face 8^k. A rod 11, is pivotally attached at its upper end to the firing member or hammer H and at its lower end is attached by passing through, or in other suitable manner, to a pivotal-pin 12, which passes through the frame-rib 10 of the grip-safety member G', the rod 11, being intended to provide a stem for an actuating or firing-spring 8° for the firing member or hammer H. A further purpose of the pivot pin 12 is hereinafter explained. The spring 8° surrounds the rod or stem 11, being seated on said pivot pin 12, and having a pivotal movement at its lower end due to movement of the pivot-pin 12, and also being movable with the grip-safety member G', when this member is compressed, and abutting a suitable face

or surface of the pivotal attachment of the rod or stem 11, to the firing member or hammer H, the pressure of the spring 8° being upward to move or force the firing member or hammer to fired position and into contact with the firing-pin of the breech action of the pistol.

When the firing member or hammer is in firing position, Fig. 2, a line drawn from the centre of pivotal attachment of the rod or stem 11, to the firing member or hammer H through the center of the pivot pin 12, will pass well to the rear of the center of the pivot-pin g which attaches the lower end of the grip-safety member G' to the grip-stock 80 of the pistol, the effect of this arrangement being that the spring 8° resists hand compression of the grip-safety member G', and returns the upper end G² thereof to engagement with the frame when such compression is relieved. A line drawn from the center of pivotal attachment of the rod or stem 11, to the firing member or hammer H through the center of the pivot-pin 12, will pass through, or slightly forward of the center 90 of said pivot-pin g when the firing member or hammer H is in fired position, Fig. 3, the effect of this latter arrangement being that the spring 8° has a tendency, to retain the grip-safety member G' in hand compressed 95 or forward position, and thus neutralizes the reaction or sting of the spring 8° upon the grip-safety member G' upon sudden arresting of the firing member or hammer upon contact with the firing-pin of the pistol, when the hammer H is actuated by the spring 8°.

The slidable member or controller N is movable upwardly and downwardly, being guided at its upper end in its sliding movement by guide-faces 13 and 14 in the frame or receiver B of the pistol, and is guided at its lower end by a vertical rib or portion of the grip-stock which acts as a guide-face, and by a pin 15, mounted in the grip-stock of the pistol, or by other means suitable for retaining the slidable member or controller in position for sliding movement and to prevent shifting thereof. The pin 15 also acts as a detent means for the slidable member or controller N. The latter is provided at its upper end with a point or face 14^a, which, when the slidable member or controller is in upward position, lies in the path of or blocks the sliding breech action 110 of the pistol in its movement.

The slidable member or controller N is provided with a shoulder 14^b having an upper engaging surface 14^c. A recess or slot 16 is provided in the slidable member or controller N to receive the end of the trigger member F, and permit a slight movement or play upward and downward of the trigger member F therein.

The lower portion of the slidable mem-

ber or controller N terminates in an extended end 17, having on its forward side an inclined face 18 and having on its rear side a face 19, having an end-face or bottom side 20.

The slideable member or controller N is provided with a spring operated actuator 14^m to move the slideable member or controller upwardly.

10 The lever member n is pivotally attached to the slideable member or controller N, and is provided with a face 21 for engaging the actuator 14^m, and with an end 22 for engaging the sear member S.

15 The sear member S is pivotally attached to the grip-stock of the pistol, and is provided with a shoulder 17^s for engaging the firing notch or cock-notch 8^s of the firing member or hammer H, and with a face 17^s

20 for engaging the eccentric cam face 8^k of the firing member or hammer, and with an arm S¹⁰ having a face 17^t for engaging the upper surface 14^e of the shoulder 14^p of the slideable member or controller, and with a

25 lever-face 17^c for engaging the end 22 of the lever-member n. The lower end 17^a of the sear member S is extended to engage the end of the trigger member F. The block-lever 23, is attached to the pivot-pin 12, and

30 supported thereby to move freely thereon, Fig. 1, and is movable inwardly by hand compression of the grip-safety member G', Fig. 2, so that the inner side or face of the upper end 24 thereof engages the extended

35 end of the trigger member F and the inner side or face of the lower end 25 thereof engages the controller-blocking member 26.

The controller-blocking member 26 is pivotally attached at the lower end of the 40 grip-safety member G', preferably by the pivot-pin 9 which secures the grip-safety member G' to the grip-stock of the pistol.

The controller-blocking-member is provided at its upper end with an end-face 27, which 45 is engageable with the inclined face 18 of the slideable member or controller N, and is provided with adjacent step-faces 28 and 29, with which the end face or bottom side 20 of the slideable member or controller

50 is engageable. An actuator 30 consisting of a spring 31, and a projector or nose-piece 32 is provided for forcing or pressing the controller-blocking member 26 upwardly, the point of the projector or nose-piece 32

55 engaging the upper surface of a rib 33, of the grip-stock of the pistol, or engaging such other means as will provide an abutment for the projector or nose-piece to cause the spring 31 to force or press the controller-blocking member 26 upwardly. The trigger member F is provided at its inner end

60 with an inclined face 34 and with an extended end 35, the purpose of the inclined face 34 being to engage the extended end

65 17^a of the sear member S after the extended

end 35 of the trigger member F has been brought into contact with the upper end 24 of the block-lever 23. The trigger member F is movable forwardly by means not shown, and by pull thereon is movable rearwardly.

In operation, when my grip-safety device is in normal position or position of safety, and the firing member or hammer H is in firing or cocked position, Fig. 1, and locked 70 in this position by the sear member S, and by cooperation therewith of the lever member n, and actuator 14^m, the slideable member or controller N being in upward position, and blocked in this position by the controller-blocking member 26, and grip-safety member G', the end 14^a of the slideable member or controller locks the sliding breechaction of the pistol against movement as described in my before mentioned 85 patent.

The slideable member or controller N is moved to this upward position by movement of the firing member or hammer H to firing or cocked position, the cam face 8^k of 90 the firing member or hammer engaging the face 17^s of the sear member S to move the sear member, the lever-face 17^c of which engages the end 22 of the lever-member n, the face 21 of which engages the actuator 14^m, 95 which moves the slideable member or controller N upwardly.

The end G² of the grip-safety member G', Fig. 1, is in engagement with the frame of the pistol. The step-face 28, of the controller-blocking member 26 is in engagement with the end-face or bottom side 20 of the slideable member or controller N, the slideable member or controller being held in this position by pressure of the end-face 27, 100 of the controller-blocking member 26 on the inclined face 18 of the slideable member or controller N, which thus holds the slideable member or controller against the pin 15.

The pin 15, thus acts as a detent means 110 to prevent inward movement or shifting of the slideable member or controller N, but instead of a pin any other suitable means for this purpose may be used. The lower end 17^a of the sear member S is out of engagement with the inclined face 34 of the trigger member F, and the arm S¹⁰ of the sear member is out of engagement with the upper surface 14^e of the shoulder 14^p of the slideable member or controller N. The upper end 24 of the block-lever 23 is contactable with the extended end 35 of the trigger member F while the lower end 25 of the block-lever is contactable with the vertical edge of the step-face 29 of the controller-blocking member 26.

Grip-compression of the grip-safety member G', Figs. 2 and 3, disengages the end G² thereof from the frame of the pistol and moves the block-lever 23 inwardly so 130

that the lower end 25 thereof is brought into contact with the vertical edge of the step-face 29, of the controller-blocking member 26, Fig. 2, the slidable member or controller N still being blocked against downward movement by the controller-blocking member 26. Pull upon the trigger member F first brings the end 35 thereof into contact with the upper end 24 of the block-lever 23, and thereby moves the end 24 inwardly or rearwardly which forces the lower end 25 thereof outwardly or forwardly, which lower end 25, already having been brought into contact with the vertical edge of the step-face 29 of the controller-blocking member 26 by compression of the grip-safety member G', forces the controller-blocking member 26 outwardly or forwardly and thereby disengages the step-face 28 from the end-face 20 or bottom side 20, of the slidable member or controller N, and permits downward movement of the slidable member or controller.

Pull upon the trigger member F next engages the inclined face 34 thereof, with the lower end 17^a of the sear member S, and moves the sear member to release the firing member or hammer H which is actuated by the spring 8^a.

Movement of the sear member S also engages, or brings into contact, by movement of the firing member or hammer H to fired position, the arms S¹⁰ thereof with the upper surface 14^e of the shoulder 14^p of the slidable member or controller N, Fig. 3, thus moving the slidable member or controller downwardly, and thereby releasing the sliding breechaction and permitting discharge of the pistol upon contact of the firing member or hammer H with the firing-pin of the sliding breechaction.

Having thus described my invention, I claim:

1. In a firearm, in combination, a frame of said firearm, a firing member movable to firing position and to fired position, sear means for engaging said firing member, slidable means, means for moving said slidable means in a direction when the firing member is moved to firing position to lock said sear means and firing member in firing position, said sear means moving said slidable means in a direction reverse to the first mentioned direction when the firing member is moved to fired position, means engageable with said slidable means for blocking the slidable means in position for locking said sear means and firing member in firing position, a grip-compressible member engageable, when in position of safety, with said frame, and releasable by grip-compression from said engagement, trigger means, means contactable, by grip-compression of the grip-compressible member, with said blocking means and with said trigger means, and spring means for moving said firing member to fired position; said trigger means being arranged by pull thereon, when said grip-compressible member is grip-compressed, to actuate primarily said contactable means and thereby move said blocking means to release said slidable means for movement by the sear means from said locking position, and to move subsequently said sear means and thereby release said firing member for movement to fired position.

2. In a firearm, in combination, a sliding breech-action of said firearm, a frame of said firearm, a firing member movable to firing position and to fired position, sear means for engaging said firing member, slidable means, means for moving said slidable means in a direction, when the firing member is moved to firing position, to lock said sliding breechaction, and lock said sear means and firing member in firing position, said sear means moving said slidable means in a direction reverse to the first mentioned direction when the firing member is moved to fired position, means engageable with said slidable means for blocking the slidable means in position for locking said sliding breechaction, and locking said sear means and firing member in firing position, a grip-compressible member engageable, when in position of safety, with said frame, and releasable by grip-compression from said engagement, trigger means, means contactable, by grip-compression of the grip-compressible member, with said blocking means and with said trigger means, and spring means for moving said firing member to fired position.

3. In a firearm, in combination, a frame of said firearm, a firing member movable to firing position and to fired position, a sear member for engaging said firing member, a slidable member provided with an actuator, a lever member engaging said actuator and engaging said sear member to move the slidable member upwardly when said firing member is moved to firing position, to lock said sear member and firing member in firing position, said sear member engaging said firing member and being engageable with said slidable member to move the slidable member downwardly when said firing member is moved to fired position, means engageable with said slidable member for blocking the slidable member in upward locking position, a grip-compressible member engageable, when in position of safety, with said frame, and releasable by grip-compression from said engagement, trigger means, means contactable, by grip-compression of the grip-compressible member, with said blocking means and with said trigger means, and spring means for moving said firing member to fired position.

3. In a firearm, in combination, a frame of said firearm, a firing member movable to firing position and to fired position, a sear member for engaging said firing member, a slidable member provided with an actuator, a lever member engaging said actuator and engaging said sear member to move the slidable member upwardly when said firing member is moved to firing position, to lock said sear member and firing member in firing position, said sear member engaging said firing member and being engageable with said slidable member to move the slidable member downwardly when said firing member is moved to fired position, means engageable with said slidable member for blocking the slidable member in upward locking position, a grip-compressible member engageable, when in position of safety, with said frame, and releasable by grip-compression from said engagement, trigger means, means contactable, by grip-compression of the grip-compressible member, with said blocking means and with said trigger means, and spring means for moving said firing member to fired position.

- sion from said engagement, a trigger-member, lever means contactable at one end thereof with said blocking means and contactable at the other end thereof with said 5 trigger member by grip-compression of the grip-operable member, and spring means for moving said firing member to fired position, and affording grip-compression of the grip-operable member, and for returning the 10 grip-operable member to engagement with said frame after grip-compression; said trigger member by pull thereon, when said grip-operable member is grip-compressed, being engageable primarily with one end of 15 said lever means to move the other end of said lever means and thereby move said blocking means to release said slidable member for movement by the sear member from upward locking position, and being engageable subsequently with said sear member to move the same to release said firing member for movement to fired position.
7. In a firearm, in combination, a frame of said firearm, comprising a grip-stock, a 20 firing hammer movable to firing position and to fired position, and provided with a cock-notch and an eccentric cam face, a sear member provided with a locking shoulder for engaging said cock-notch and 25 a face for engaging said eccentric cam face, and provided with an arm, and provided with a lever-face, and provided with a lower end, a slidable controller provided with a spring-operated actuator, and provided with 30 a shoulder having an upper engaging surface, and provided with means for receiving a trigger member, and provided with a bottom-face, and provided with an inclined face, guide-face and pin means for guiding said 35 slidable controller in its sliding movement and preventing shifting movement thereof, a lever member pivotally attached to said slidable controller and provided with a face for engaging said actuator, and with an 40 end-face for engaging said lever-face of the sear-member, to move said slidable controller upwardly when said firing hammer is moved to firing position, said sear member being disengageable from the firing hammer and 45 said arm of the sear member being engageable with said upper engaging surface of the shoulder of the slidable controller to move the controller downwardly when said firing hammer is moved to fired position, a 50 blocking member pivotally attached to said grip-stock and provided with an end-face for engaging said inclined face of the slidable controller, and provided with upper and lower step-faces for respectively engaging 55 said bottom-face of the slidable controller when the controller is in upward and downward positions, spring means for moving said blocking member upwardly, a grip-safety member pivotally attached at its 60 lower end to said grip-stock, and engageable 65 at its upper end with said frame when in position of safety, and releasable by grip-compression from said engagement at its upper end, a block-lever supported on said grip-safety member to move freely and provided with an upper end contactable with a trigger member and a lower end contactable with said blocking member when said safety member is grip-compressed, and a trigger member engaging said receiving 70 means of the slidable controller and provided with an end-face for engaging primarily said upper end of said block-lever and a recess-face for engaging subsequently said lower end of the sear member by pull 75 on said trigger member when said grip-safety member is grip-compressed, and a spring pivotally attached at its upper end to said firing hammer and pivotally seated at its lower end and movable with said grip-safety member when said member is grip-compressed, to actuate said firing hammer, and afford grip-compression of the grip-safety member, and to return the same to position of safety after grip-compression, 80 and to neutralize the reaction of said spring on said grip-safety member upon sudden arresting of said firing hammer when actuated by said spring.
8. In a firearm, in combination, a sliding breechaction of said firearm, a frame of said firearm comprising a grip-stock, a firing hammer movable to firing position and to fired position, and provided with a cock-notch and an eccentric cam face, a sear 85 member provided with a locking shoulder for engaging said cock-notch and a face for engaging said eccentric cam face, and provided with an arm, and provided with a lever face, and provided with a lower end, a slidable controller provided with means for engaging said sliding breechaction, and provided with a spring-operated actuator, and provided with a shoulder having an upper engaging surface, and provided with 90 means for receiving a trigger member, and provided with a bottom-face, and provided with an inclined face, guide-face and pin means for guiding said slidable controller in its sliding movement and preventing 95 shifting movement thereof, a lever member pivotally attached to said slidable controller and provided with a face for engaging said actuator and with an end face for engaging said lever face of the sear member, to move 100 said slidable controller upwardly when said firing hammer is moved to firing position to lock said sliding breechaction, and lock said sear member and firing member in firing position, said sear member being disengageable from the firing hammer and said arm of the sear member being engageable with 105 said engaging surface of the shoulder of the slidable controller to move the controller downwardly when said firing ham- 110
- 115
- 120
- 125
- 130

mer is moved to fired position, a blocking member pivotally attached to said grip-stock and provided with an end-face for engaging said inclined face of the slidable controller, and provided with upper and lower step-faces for respectively engaging said bottom-face of the slidable controller when the controller is in upward and downward positions, spring means for moving 5 said blocking member upwardly, a grip-safety member pivotally attached at its lower end to said grip-stock, and engageable at its upper end with said frame when in position of safety, and releasable by grip-compression from said engagement at its upper end, a block-lever supported on said grip-safety member to move freely and provided with an upper end contactable with a trigger member and a lower end contactable 10 with said blocking member when said grip-safety member is grip-compressed, a trigger member engaging said receiving means of the slidable controller, and provided with an end-face for engaging primarily said 15 upper end of the block lever and a recess-face for engaging subsequently said lower end of the sear member by pull on said trigger-member when said grip-safety member is grip-compressed, and a spring pivotally 20 attached at its upper end to said firing hammer and pivotally seated at its lower end and movable with said grip-safety member when said member is grip-compressed to actuate said firing hammer, and afford compression of the grip-safety member, and to 25 return the same to position of safety after grip-compression, and to neutralize the reaction of said firing hammer on said grip-safety member upon sudden arresting of 30 said firing hammer when actuated by said spring.

9. In a firearm, in combination, a firing member movable to firing position and to fired position, sear means engageable with 35 said firing member, trigger means, slidable means movable in a direction to lock said sear means and firing member in firing position, and movable in a direction to unlocking position reverse to the first mentioned direction when said firing member is moved to fired position, means for blocking said slidable means in position for locking said sear means and firing member in firing 40 position, and means contactable with said blocking means and with said trigger means by grip-compression, said trigger means being engageable primarily with said contactable means when the contactable means is grip-compressed, to move said blocking means to release said slidable means for movement from locking position, and being engageable subsequently with said sear member to move the same to release said firing member for movement to fired position.

50 10. In a firearm, in combination, a sliding breechaction of said firearm, a firing member movable to firing position and to fired position, a sear member for engaging said firing member, a trigger member, slidable means movable in one direction to lock said sliding breechaction, and lock said sear member and firing member in firing position, and movable in a reverse direction to unlocking position when said firing member is moved to fired position, means for guid-

breechaction of said firearm, a firing member movable to firing position and to fired position, sear means for engaging said firing member, trigger means, slidable means movable in a direction to lock said sliding breechaction, and lock said sear means and firing member in firing position, and movable in a direction reverse to the first mentioned direction to unlocking position when said firing member is moved to fired position, means for blocking said slidable means in position for locking said sliding breechaction and locking said sear means and firing member in firing position, and means contactable with said blocking means and with 50 said trigger means by grip-compression, said trigger means being engageable primarily with said contactable means, when the contactable means is grip-compressed, to move said blocking means to release said slidable means for movement from locking position, and being engageable subsequently with said sear means to move the same to release said firing member for movement to fired position.

90 11. In a firearm, in combination, a firing member movable to firing position and to fired position, a sear member for engaging said firing member, a trigger member, slid- 95 able means movable in one direction to lock said sear member and firing member in firing position, and movable in a reverse direction to unlocking position when said firing member is moved to fired position, means for guiding said slidable means in its sliding movement and preventing shifting movement thereof, means for blocking said slid- 100 able means in position for locking said sear member and firing member in firing position and retaining said slidable means in engagement with said guiding and shift-preventing means when in such locking position, and means contactable with said blocking means and with said trigger member by grip-com- 110 pression, said trigger member being engageable primarily with said contactable means when the contactable means is grip-compressed, to move said blocking means to release said slidable means for movement from locking position, and being engageable subsequently with said sear member to move the same to release said firing member for movement to fired position.

115 12. In a firearm, in combination, a sliding breechaction of said firearm, a firing member movable to firing position and to fired position, a sear member for engaging said firing member, a trigger member, slidable means movable in one direction to lock said sliding breechaction, and lock said sear member and firing member in firing position, and movable in a reverse direction to unlocking position when said firing member is moved to fired position, means for guid-

120 130 13. In a firearm, in combination, a sliding breechaction of said firearm, a firing member movable to firing position and to fired position, a sear member for engaging said firing member, a trigger member, slidable means movable in one direction to lock said sliding breechaction, and lock said sear member and firing member in firing position, and movable in a reverse direction to unlocking position when said firing member is moved to fired position, means for guid-

- ment and preventing shifting movement thereof, means for blocking said slidable means in position for locking said sliding breechaction and locking said sear member 5 and firing member in firing position, and retaining said slidable means in engagement with said guiding and shift-preventing means when in such locking position, and means contactable with said blocking means 10 and with said trigger means by grip-compression, said trigger member being engageable primarily with said contactable means, when the contactable means is grip-compressed, to move said blocking means to release said slidable means for movement from locking position, and being engageable subsequently with said sear member to move the same to release said firing member for movement to fired position.
- 15 20 13. In a firearm, in combination, a frame of said firearm comprising a grip-stock, a firing member movable to firing position and to fired position, a grip-compressible member engageable with said frame and pivotally attached to said grip-stock, a rod pivotally attached at one end to said firing member and attached at the other end to said grip-compressible member, and a spring surrounding said rod and abutting the 25 pivotal attachment of said rod to said firing member, and seated at the point of attachment of said rod to said grip-compressible member.
14. In a firearm, in combination, a frame of said firearm comprising a grip-stock, a firing member movable to firing position and to fired position, a grip-compressible member engageable with said frame and pivotally attached to said grip-stock, and provided with a frame-rib, a pivot pin in said frame-rib, a rod pivotally attached at one end to said firing member and secured at the other end to said pivot pin, and a spring surrounding said rod, and abutting the 30 pivotal attachment of said rod to said firing member and seated on said pivot pin.
- 15 35 15. In a firearm, in combination, a frame of said firearm comprising a grip-stock, a firing member movable to firing position and to fired position, a grip-compressible mem-
- ber engageable at one end with said frame and pivotally attached at the other end to said grip-stock, and provided with a frame rib, a pivot-pin in said frame rib, a rod pivotally attached at one end to said firing member and secured at the other end to said pivot-pin, and a spring surrounding said rod and abutting the pivotal attachment of said rod to said firing member and seated on said pivot-pin; a line through the center of 40 pivotal attachment of said rod to said firing member and through the center of said pivot-pin passing, when said firing member is in firing position and said end of the grip-compressible member is in engagement with 45 said frame, through or slightly to the rear of the center of pivotal attachment of said grip-compressible member to said grip-stock.
16. In a firearm, in combination, a frame of said firearm comprising a grip-stock, a 50 firing member movable to firing position and to fired position, a grip-compressible member engageable at one end with said frame and pivotally attached at the other end to said grip-stock, and provided with a frame-rib, a pivot-pin in said frame-rib, a rod pivotally attached at one end to said firing member and secured at the other end to said pivot-pin, and a spring surrounding said 55 rod and abutting the pivotal attachment of said rod to said firing member and seated on said pivot-pin, a line through the center of pivotal attachment of said rod to said firing member and through the center of said pivot-pin passing, when said firing member is in firing position and said end of said 60 grip-compressible member is in engagement with said frame, through or slightly to the rear of the center of pivotal attachment of said grip-compressible member to said grip-stock.
